Primary Examiner — Zenia I Bennett(74) *Attorney, Agent, or Firm* — Brooks Kushman P.C.(57) **CLAIM**

The ornamental design for a self-inking eyeliner pen, as shown and described.

DESCRIPTION

FIG. 1 is a perspective view of a self-inking eyeliner pen according to one embodiment;

FIG. 2 is a front side view of the self-inking eyeliner pen of FIG. 1;

FIG. 3 is a back side view of the self-inking eyeliner pen of FIG. 1;

FIG. 4 is a left side view of the self-inking eyeliner of FIG. 1;

FIG. 5 is a right side view of the self-inking eyeliner of FIG. 1;

FIG. 6 is a first embodiment of the bottom end view of the self-inking eyeliner of FIG. 1; and,

FIG. 7 is a top end view of the self-inking eyeliner of FIG. 1.

The broken lines show portions of the article not claimed and form no part of the claimed design.

1 Claim, 3 Drawing Sheets(56)
